UNITED STATES PATENT OFFICE.

FRANCIS M. CROSSLEY, OF REDFORD, MICHIGAN.

SWITCH POINT.

Application filed September 26, 1919. Serial No. 326,548.

To all whom it may concern:

Be it known that I, FRANCIS M. CROSSLEY, a citizen of the United States of America, residing at Redford, in the county of Wayne 5 and State of Michigan, have invented certain new and useful Improvements in Switch Points, of which the following is a specification, reference being had therein to the accompanying drawings.

10 The track equipment of electrically operated railways includes switch points provided with devices for maintaining the switch points in adjusted positions, and one of the devices at present used includes a 15 multiplicity of parts which are not at all satisfactory due to the elements interfering with their operation and the least wear permitting of a switch tongue to accidentally shift, causing derailments. Furthermore, the devices 20 require considerable space, constant attention, and often prevent a motorman or switch operator from manually throwing the switch point.

My invention aims to provide positive and 25 reliable means, in a manner as hereinafter set forth, for holding a switch tongue after being shifted, and the means employed is of such a nature that should a switch point be only partially actuated said means will 30 either restore the switch point to normal position or complete the actuation of the same. In other words, there is no intermediate position for the switch point and consequently derailments are avoided.

35 My invention further aims to provide a simple, durable and inexpensive switch point holding device that may be easily and quickly installed, occupies a comparatively small space, and is applicable to the switch tongues 40 of various kinds of railways.

My invention will be hereinafter considered and then claimed, and reference will now be had to the drawing wherein—

Figure 1 is a plan of an electric railway 45 switch provided with a switch tongue holding device in accordance with my invention;

Fig. 2 is a cross sectional view of the device;

Fig. 3 is a horizontal sectional view taken 50 on the line III—III of Fig. 2;

Fig. 4 is a perspective view of another type of railway switch provided with a tongue holding device;

Fig. 5 is a plan of the device, and

55 Fig. 6 is a plan of a railway switch of a

heavier type provided with devices in accordance with my invention.

Considering Figures 1, 2 and 3, showing the preferred form of construction, the reference numeral 1 denotes a switch mate and 60 associated therewith is a switch tongue housing 2 having a switch tongue 3 pivoted in the usual and well known manner so that it may be swung in a lateral plane for switching rolling stock on rails connected to the mate 65 1 and the switch point housing 2.

The top of the housing 2 has an opening 4 providing clearance for a depending lug 5 carried by the switch tongue 3, intermediate the ends thereof, and connected to said 70 lug is a bolt or slide bar 6 extending through an opening 7 in the side of the housing 2 into a casing 8 connected to the side of the housing 2 by bolts 9 or other fastening means. The casing 8 may be formed integral with the housing 2 and be devoid of a bottom plate, but in all instances said casing has a detachable cover plate 10.

On the bolt 6, against the lug 5, is a sleeve 11 serving as a spacer member for a 80 double conical-shaped head 12 mounted on the outer end of the bolt 6 and retained thereon by nuts 13 or other fastening means. The double conical-shaped head 12 presents two annular beveled or rounded faces and 85 one of these faces is always engaged by the indent portions 14 of spring arms 15 forming part of a one-piece spring or resilient member 16 connected to a wall of the casing 8 by fastening means designated 17. The 90 spring arms 15 are opposed and serve somewhat as a snap fastener or automatic cap and with the head 12 constantly between the spring arms said arms are held under tension exerting a constant pressure against 95 the head 12 so that the switch tongue 3 will be held against either of the walls 18 or 19 of the housing 2. The housing 2 has recesses 20 so that a tongue throwing rod or tool may be placed against either side of the 100 switch tongue 3 to shift it from one position to another. Considering Figure 1 and assuming that the tongue 3 is to be shifted, a movement of the head 12 between the spring arms 15 and towards the outer end of the 105 spring causes the arms to move apart until the large and central portion of the head passes the indent portions 14 of the spring arms, when said indent portions engage the other face of the head and positively hold 110

the head against accidental displacement. When shifting the tongue 3 should the operator neglect to completely throw the tongue the spring arms 15 will either restore 5 the switch tongue to normal position or completely shift the same. The latter instance is particularly true should the operator of the switch tongue impart sufficient impetus thereto to cause the head 12 to ride over 10 the apex of each of the indent portions 14 of the spring arms 15, and it is in consequence of this construction that the switch tongue cannot be left in an intermediate position.

To facilitate installing the device and particularly the bolt 6, the housing 2 may have 15 an auxiliary casing 21 communicating with the housing 2 through a side opening 22, said opening aligning with the bolt 6 so that access may be had thereto. In some instances the auxiliary casing 21 may be dispensed with.

Considering Figs. 4 and 5, there is shown another type of switch embodying a rail 23 having a switch point 24 movable to and 25 from said rail, said switch point being connected to a slide bar 25 adapted to be actuated by a link 26 and a lever actuated crank 27. These elements are of a conventional 30 form and are illustrated as an example of switch throwing devices used on steam railroads.

Adjustably connected to the inner side of the rail 23 is a spring arm or resilient member 28 having an apex or bent portion 29 adapted to engage the end of the tongue 24, said spring arm lying at a right angle to the 35 switch point with the point constantly in engagement therewith, so that the apex or bent portion 29 of the device will retain the 40 switch point either in a closed or open position relative to the rail 23. With the device adjustably connected to the web of the rail it may be shifted to compensate for wear on the extreme end of the switch point and its 45 location does not interfere with the flange of a wheel moving over the rail or switch point.

A somewhat similar switch is shown in Fig. 6 as having a slide bar 30 for switch 50 tongues or points 31. A switch throwing device and semaphore signal, generally designated 32, is operatively connected by a rod 33 to the slide bar 30 and the connecting bolt or pin 34 is slightly longer than the usual bolt or pin, so as to accommodate a

head or roller 35. Since a roller possesses 55 two convex or somewhat conical faces it will serve its purpose as well as the head 12 previously referred to.

On the ties adjacent the bolt 34, is a casing 36 containing a spring or resilient retaining 60 member 37 that is normally engaged by the head or roller 35, and the rod 33 and slide bar 30 may extend under or through the casing. The retaining member 37 yieldably holds the head or roller 35 so that the switch throwing device 32 may operate the switch, otherwise, the switch points or tongues 31 65 cannot be accidentally shifted by rolling stock.

In some instances the slide bar 30 may extend 70 into another holding device 38 at the opposite side of the track, and this simple construction is in contra-distinction to those devices, some of which have twenty or more parts, which must receive constant attention 75 and cannot be relied upon, particularly in cold weather, to hold a switch in an adjusted position.

The structural elements of my invention 80 are susceptible to such variations and modifications as fall within the scope of the appended claim.

What I claim is:—

In a switch point housing wherein a switch point has a slide bar extending from the 85 housing and by which the switch point may be held in an adjusted position:—means at the side of said housing for holding the bar of said switch point, said means comprising a casing having an end wall, a resilient 90 member having its middle portion connected to the end wall of said casing and provided with opposed bowed portions adjacent the end wall of the casing, the bowed portions terminating in arms having opposed indent 95 portions, and a head on the slide bar of said switch point adapted to be forcibly shifted between the indent arm portions of said resilient member so that said resilient member, head, and switch housing may cooperate in 100 holding the switch point in an adjusted position.

In testimony whereof I affix my signature in the presence of two witnesses.

FRANCIS M. CROSSLEY.
